DESIGN FOR AN ADJUSTABLE HOSIERY BLOCKER AND DRIER

John L. Devaney, Oak Park, Ill., assignor to Frank J. Bolek, Chicago, Ill.

Application December 9, 1940, Serial No. 97,205

Term of patent 7 years

To all whom it may concern:

Be it known that I, John L. Devaney, a citizen of the United States, residing at Oak Park, in the county of Cook and State of Illinois, have invented a new, original, and ornamental Design for an Adjustable Hosiery Blocker and Drier, of which the following is a specification, reference being had to the accompanying drawing, forming part thereof.

able hosiery blocker and drier, showing my new design.

I claim:

The ornamental design for an adjustable hosiery blocker and drier, as shown.

JOHN L. DEVANEY.
